United States Patent Office.

GEORGE DAYSPRING AND EDWARD FITZKI, OF WASHINGTON,
DISTRICT OF COLUMBIA.

Letters Patent No. 94,720, dated September 14, 1869.

IMPROVEMENT IN CLOTH-SPONGING MACHINES.

The Schedule referred to in these Letters Patent and making part of the same.

To all whom it may concern:

Be it known that we, GEORGE DAYSPRING and EDWARD FITZKI, of the city of Washington, county of Washington, and District of Columbia, have invented a new and useful Cloth-Sponging Machine; and we do hereby declare that the following is a full, clear, and exact description of the construction and operation of the same, reference being had to the annexed drawings, making a part of this specification, in which—

Figure 1 represents a front view of that part of the machine which is used for wrapping and unwrapping the cloth to be sponged.

Figure 2 represents a front view of the whole machine.

Similar letters of reference indicate like parts.

This invention consists in a cloth-sponging machine, made in several parts, viz, a boiler with a gauge and draw-off cock; a curved pipe on the top of the boiler, to connect with a similar-sized pipe; and a part of a cylinder, which, being perforated with innumerable small holes, receives the steam and allows it to escape, to penetrate the cloth wrapped around it.

To keep the cylinder in proper position, a small stand, made of wood or any other suitable material, is placed underneath the disconnected end of the cylinder, to keep the latter in a perfect level or horizontal position.

To effect the wrapping of the cloth upon and unwrapping from the cylinder, another stand, of suitable material, receives the cylinder in two grooves provided with caps.

To suit the height of the different tables, we refer to the minute description of this stand given below.

The boiler, provided with water, is placed upon a stove or range containing fire. The steam raised through the boiling of the water will pass through the pipe on top of the boiler to the cylinder, and thence through the small holes of the latter into the cloth wrapped around it, shrinking thereby the cloth to its proper state, and preserving a beautiful gloss and the color of the cloth. The latter having remained a sufficient time, is taken off to dry, when it will be ready for use.

A represents a stand, made of wood, iron, or any other suitable material, with a foot, b, and two uprights, a' a'', at right angles thereto, each upright being surmounted by a cap, c, which is a part of a'.

The caps c are made in two parts, connected on the back with hinges, in front with a hook, d, and a catch, d'. They are horizontally grooved, for the purpose of receiving the journals of the cylinder B, made of tin, brass, or any other suitable material, and of any desired size, part e being perforated with innumerable small holes.

We do not confine ourselves to the size nor to the shape of the cylinder. Its size must be regulated to the work to be done, and may be from three to eighteen inches, more or less, in diameter, as also the shape may be round or oval.

The cylinder B is provided with funnel-shaped pieces, g g', on each end.

g being closed up, has on the end a knob or crank, h, of wood or any other suitable material, for the purpose of turning the cylinder in the above-mentioned journal-boxes or caps c c' of A.

The piece g' is a pipe, to connect with the hollow of the cylinder.

To guide the even wrapping of the cloth upon the cylinder, we provide the latter with flanges f f' and f' f.

The cloth to be sponged is placed upon a table, and to suit the height of the cylinder to that of the table, we construct in our stand a piece, b', which is connected with and is a part of a' a'.

We make a dovetailed groove in a and a', and provide a' and a'' with a dovetailed tongue, which, fitting into each other, will easily work, sliding up and down, and cannot come apart.

By taking hold of b', we can adjust the cylinder to any desired height, by means of a pin, m, held by a small chain, n, the latter secured at a hook, o, to be thrust into a hole made through a and a' on both sides. These holes are made at regular and equal distances at both sides.

The desired height of the cylinder, with regard to the table, being obtained, and a piece of canvas being wrapped around the cylinder part e, the cloth is guided by the flanges f f' and f' f', and wrapped upon the cylinder, as shown in fig. 1, by turning the knob or crank h.

Having all the cloth upon the cylinder we desire to sponge at one time, we detach the hooks d d', open the caps c c', and take the cylinder therefrom, and connect g' with the boiler-pipe p, below described, and g we place upon another stand, D, as shown in fig. 2, constructed on the same principle and of the same material as stand A, h and i representing a and a'.

C represents a boiler, made of tin, brass, iron, or any other suitable material, and of any size required for the amount of steam necessary, with a round top, s, and an open pipe, p, soldered thereon at the middle, p', to connect at t with g', and for the purpose to convey the steam from the boiler C, through p and g', to the cylinder B.

For the regulation of the steam, we attach, at q, a gauge-cock, and to relieve the boiler of all water after its use, we attach, at q', a draw-off cock, both to be worked with a lever, r.

The advantages of this cloth-sponging machine are apparent, and require no further explanations.

The sponging of the cloth by steam is more effectual, it penetrating and shrinking the cloth more, and preserving the gloss of the same better, than the old way by wet linen.

We claim as new, and desire to secure by Letters Patent—

In cloth-sponging machines, the combination and

arrangement of the supporting-stand A, perforated cylinder e, boiler C, and connecting steam-pipe p, as and for the purpose set forth.

GEORGE DAYSPRING.
EDWARD FITZKI.
